US00D899513S

(12) **United States Design Patent** (10) Patent No.: **US D899,513 S**
(45) Date of Patent: **** Oct. 20, 2020**

(54) **INK CARTRIDGE FOR COMPUTER PRINTER**

(71) Applicant: **CANON KABUSHIKI KAISHA**,
Tokyo (JP)

(72) Inventors: **Tetsuya Ohashi**, Tokyo (JP); **Takashi Fukushima**, Tokyo (JP); **Hironori Murakami**, Tokyo (JP); **Ryoji Inoue**, Tokyo (JP); **Takeho Miyashita**, Tokyo (JP); **Yasuo Kotaki**, Tokyo (JP); **Kyosuke Nagaoka**, Tokyo (JP)

(**) Term: **15 Years**

(21) Appl. No.: **35/507,171**

(22) Filed: **Sep. 28, 2018**

(80) **Hague Agreement Data**

Int. Filing Date: **Sep. 28, 2018**

Int. Reg. No.: **DM/201966**

Int. Reg. Date: **Sep. 28, 2018**

Int. Reg. Pub. Date: **Aug. 2, 2019**
